INSTRUMENT FOR DETERMINING
RELATIVE LEVELS

Joseph John Wisney, Adrian, Mich.

Application March 12, 1949, Serial No. 81,070

1 Claim. (Cl. 137—39)

1

The present invention relates to instruments for determining relative levels, and has among its objects the provision of means for measuring the comparative levels or height of two surfaces.

Another object is means by which the relative height of two surfaces may be ascertained directly and accurately whether they are adjacent each other or more or less widely separated.

Another object is means by which such relative heights may be measured without reference to a base line or surface.

Still other objects and advantages will be apparent to those skilled in the art upon reference to the following description and the accompanying drawings in which

Fig. 1 is a view in elevation of the device.

Fig. 2 is a side elevation of one of the units with parts in section.

Fig. 3 is a central vertical section of the valved upper end of such unit.

Fig. 4 is a section on line 4—4 of Fig. 3.

Fig. 5 is a section on line 5—5 of Fig. 2.

As indicated in the drawing, the device consists essentially of two substantially identical units connected by a flexible conduit and containing a suitable quantity of a suitable liquid.

Each of these units consists of a transparent cylindrical vessel consisting of a transparent tube 10 of glass or other suitable material mounted on a bottom member 11 provided with a downwardly opening socket 11A in which fits a pin 11B, the other end of which fits in a similar upwardly opening socket 11C formed on a base member 11D. Bottom member 11 is preferably square.

The upper end of tube 10 is closed by means of a suitable preferably square cap 12 having a central opening 12A, and on three sides of the square cap 12 and bottom member 11, plates 10A serve to protect the tube 10, which is preferably clamped between the two members by means of the longitudinally extending rods 10B passing through the corner portions.

The three plates 10A extend well above the cap 12 and these together with a fourth plate 10C provide for a chamber 13 above the cap 12, the upper wall of the chamber being the lower face of a plug member 14 fixed between the plates 10A and 10C and provided with a central axial opening or passage 14A.

The upper end of the plug 14 presents a curved surface 14C flaring outward and upward from the axial opening 14A, while a suitable cap plate 15 covers the upper ends of the plates 10A and 10C and fixes the position of plug 14 by means

2

of suitable screws 15A. Plate 15 is also provided with a vent 15B.

Mounted in the axial opening 14A of plug 14 is a plunger 16, this being of such length as to extend from the bottom face of the plug to the beginning of the flared surface 14C. This plunger 16 is, as shown in Fig. 4, fluted to provide for the easy flow of air between chamber 13 and the chamber between the plug 14 and plate 15, and is held in place by means of a pin or screw 16A extending through the plug 14 and into a vertically arranged slot 16B, the slot being of sufficient length to permit a small vertical movement of the plunger 16.

Fixed to the bottom face of plug 14 around the opening 14A is a cage member 17 in which lies a ball 17A of a diameter somewhat larger than that of opening 14A and adapted, when moved upwardly, to act as a valve therefor to close the same. Supporting the ball 17A is a plurality of flat springs 18 fixed to the cage 17 and extending under the ball.

Loosely enclosed in chamber 13 is a float 20 and loosely enclosed in the chamber 15C above plug 14 is a second ball 21. This second ball should be of such weight that when the float is resting on cap 12 and therefore not exerting an upwardly thrust on ball 17A, the plunger 16 will be moved downwardly to move the ball 17A away from the opening 14A. These parts should also be so proportioned that inflow of liquid to chamber 13 through opening 12A will cause the float to lift ball 17A, plunger 16 and ball 21, and close the opening 14A.

Fixed to the bottom member 11 and extending axially upward within tube 10 to near the top is a suitable rod 30 provided with suitable graduations. Member 11 is also provided with a suitable passage 31 opening to the space within the tube 10 and extending to the outside and opening into a suitable valve or stopcock 32, to the other side of which is attached the flexible conduit 33 extending to and connected with a similar valve 33 on the other unit. Both units are, as stated above, substantially identical.

In preparing the device for use, a suitable liquid will be put into the tubes 10 and conduit 33 in sufficient quantity to fill the device to about half the height of rods 30 when the two units are standing upon the same level surface. When this has been done, if one unit is removed to a surface of a different height, the relative heights of the two surfaces may be determined directly from the graduations on the rods 30 since the liquid will flow from the higher to the lower

unit. If the two surfaces differ in height more than half the height or length of rods 30, the pin 11B of the lower unit may have substituted for it another pin of known greater length so as to compensate for the limited movement of the liquid surface.

It is of course obvious that the common axis of pin 11B, rod 30 and tube 10 should be accurately perpendicular to the plane of the bottom face of base 11D. It is also obvious that more than two units may be used if it is desired to determine the relative heights of more than two surfaces.

By providing a valve structure such as that shown in Figs. 3 and 4, provision is made against loss of liquid due to elevating one unit too high or due to a unit's assuming a horizontal position through accident or otherwise.

When one unit is elevated sufficiently to cause the other to more than fill, such excess liquid causes the float 20 to rise and force the ball 17A upwardly and close the opening 14A. On the other hand, when a unit is in a horizontal position, the ball 21 will move out of contact with the plunger 16 and allow the springs 18 to move the ball 17A in sealing position.

I claim:

In an instrument for determining the relative height of two surfaces, a vertically arranged cylindrical vessel adapted to contain liquid, means for varying the liquid level therein, a closure for the upper end of said vessel adapted to prevent overflow of said liquid, said closure including a

chamber in open communication with the top of said vessel and enclosing a float, a passage leading from said chamber from a point directly above said float, a valve for said passage, spring means within said chamber and tending to close said valve and a weighted member adapted to overcome the spring means and maintain said valve in open position when said vessel is in upright position but adapted to be displaced when said vessel is in horizontal position whereby to allow said spring means to close said valve, said float, upon admission of sufficient fluid to said chamber to lift it to its uppermost position, contacting said spring means and enabling the latter to close the valve.
